UNITED STATES PATENT OFFICE.

JAMES WATSON, OF MARINETTE, WISCONSIN.

FLAT STOVE.

1,282,153.

Specification of Letters Patent.

Patented Oct. 22, 1918.

Application filed January 8, 1918. Serial No. 210,906.

To all whom it may concern:

Be it known that I, JAMES WATSON, a citizen of the United States, residing at Marinette, in the county of Marinette and 5 State of Wisconsin, have invented a new and useful Flat Stove, of which the following is a specification.

The device forming the subject matter of this application is a folding stove of the kind used by campers, prospectors and others, and one object of the invention is to provide a stove of the kind above specified, which can be folded readily into small compass when not in use. 10 Another object of the invention is to provide a reinforcement for the top of the stove, the reinforcement serving, also, as a baffle, and being so mounted that it can be folded flat against the top of the stove when 15 the stove is collapsed.

Another object of the invention is to provide novel means for holding the legs of the stove in place.

A further object of the invention is to provide novel means whereby the stack or chimney may be held on the stove.

It is within the province of the disclosure to improve generally and to enhance the utility of devices of that type to which the 30 present invention appertains.

With the above and other objects in view which will appear as the description proceeds, the invention resides in the combination and arrangement of parts and in the 35 details of construction hereinafter described and claimed, it being understood that changes in the precise embodiment of the invention herein disclosed can be made within the scope of what is claimed, without departing from the spirit of the invention.

In the drawings:

Figure 1 shows in side elevation, a stove constructed in accordance with the invention;

Fig. 2 is a vertical longitudinal section of the stove;

Fig. 3 is a transverse section of the stove;

Fig. 4 is a perspective view wherein the stove is shown folded up;

Fig. 5 is a perspective view showing the means whereby the chimney is held on the stove;

Fig. 6 is a side elevation showing a portion of the structure delineated in Fig. 5;

Fig. 7 is a perspective view showing the 55 means whereby the legs are held in place;

Fig. 8 is a sectional detail wherein a modified method of using the stove is depicted.

The stove forming the subject matter of this application preferably is made of metal 60 throughout, sheet iron ordinarily being employed. The stove comprises a top 1 having a depending flange 2. Side walls 3 are united by hinges to opposed portions of the flange 2, the hinges preferably being in the 65 form of knuckles 4 receiving pivot rods 5. The side walls 3 are hinged to the flange relatively near to the lower edge of the flange, intermediate the upper and lower edges of the flange, as an inspection of Fig. 70 4 will make manifest. The side walls 3 are supplied with rectangularly disposed inwardly projecting lips 6. An end wall 7 is hinged in the angle defined by a part of the flange 2 and the top 1, the hinge embodying knuckles 8 and a pivot rod 9. A vertically swinging door 10 is disposed opposite to the end wall 7 and is united by knuckles 11 and a pivot rod 12 to the extreme lower edge of one end portion of the 80 flange 2. The door 10 has rectangularly disposed side lips 14, the lower edge of the door being supplied with a bead 15. There is an opening 16 in the door 10 near the bead 15, as shown to best advantage in Fig. 85 4. An eye 17 on one end of a handle 18 is pivotally mounted in the opening 16, the handle being of use for opening and closing the door 10 and for propping the door in an open position. When the door 10 is in 90 a closed position, a projection 18' on the handle 18 is engaged in the ground, the handle thus constituting a means for holding the door closed.

Cross rods 19 are terminally mounted in 95 opposed portions of the flange 2 close to the top 1. Truss plates 20 are disposed beneath the top 1, the truss plates preferably tapering toward their ends as shown at 21 in Fig. 3.

The truss plates 20 have sockets 22 receiving the cross rods 19, the truss plates, therefore, being pivotally mounted so that they may hang in the depending positions shown in Figs. 2 and 3, or be turned up flat against the top 1. The truss plates 20, as 100 105 their name indicates, serve to reinforce and sustain the top 1, and further, they act as baffles for the products of combustion pro-

ceeding toward the flue 43, hereinafter described.

The numeral 23 denotes a pair of rear legs, which preferably are pointed as shown at 25, so that they can be driven into the ground readily. The upper ends of the legs 23 are united with the side walls 3, near to the end wall 7, by means of pivot elements 25. Figs. 1, 2, and 7 will show that the legs 23 are broad enough so that they project outwardly to a slight extent beyond the end wall 7. The legs 23 are provided in their upper edges and in their outwardly extended portions with seats 26. Vertically swinging latches 27 are pivoted at 28 to the end wall 7 and are supplied in their lower edges with seats 29 adapted to coöperate with the seats 26 in the legs 23. Pointed forward legs 30 are provided, and the same are united by means of pivot elements 31 with the side walls 3, near to the vertically swinging door 10. The top 1 of the stove is supplied, near to the end wall 7, with a draft opening 32. Flanges 42 project upwardly from the top 1, about the opening 32, as seen best in Fig. 5. The top 1 is provided, on opposite sides of the opening 32, with eyes 33 and 38. A locking frame 35 is shown, the same preferably being of L-shape and comprising rectangularly disposed arms 34 and 36. The arm 34 is pivotally mounted, near to its outer edge, in the eyes 33. The numeral 40 denotes an L-shaped frame comprising rectangularly disposed arms 39 and 41, the arm 39 being pivotally mounted, near to its outer edge, in the eyes 38. The arms 34 and 39 of the frames are parallel to each other, and the same observation holds true with respect to the arms 36 and 41. For a purpose to be described hereinafter, one end of the arm 34 is spaced, as shown at 37, from the top 1 of the stove.

The numeral 43 marks a rectangular flue which preferably is of collapsible form.

45 The flue is not described in detail, because it has been claimed in my copending application Serial No. 208,594 filed on the 24th of December, 1917, for Letters Patent on an elbow. The lower end of the flue 43 is provided with an outstanding foot or flange 44.

When the stove is set up for use as shown in Figs. 1, 2 and 3, the coöperation between the various parts is as follows: The walls 3 and 7 are disposed in depending relation with respect to the top 1, the lips 6 on the side walls 3 overlapping the outer face of the end wall 7, as shown in Fig. 7. If the door 10 is closed, the lips 14 on the door overlap the outer faces of the walls 3. The legs 30 and 23 are disposed in depending positions and the latch 27 is swung downwardly until the seat 29 in the latch coöperates with the seat 26 in the leg 23. This arrangement accomplishes two results: first, the legs 23 are held against swinging on the

7 pivot elements 25; and second, the end wall 7 is prevented from swinging inwardly. The truss plates 20 are disposed at right angles to the top 1 so as to reinforce the top and to serve as baffles for the products of combustion as the same move toward the stack 43. The stack 43 is placed on the top 1 about the flange 42, the foot 44 of the flue extending outwardly. The arms 41 and 36 of the frames 40 and 35 are swung downwardly, the foot 44 on the flue being engaged by the arms 34 and 36 of the frame 35, and being engaged by the arms 39 and 41 on the frame 40. The arm 41 has sufficient resiliency so that its free end may be engaged beneath the end 37 of the arm 34 and when the parts are arranged as above described, the flue 43 will be held securely, in upright position, on the top 1 of the stove.

In order to collapse the stove and dispose the same as shown in Fig. 4, the stove is inverted, and the truss plates 20 are folded flat against the top 1, it being recalled that the stove has been inverted from the position of Fig. 1. The end wall 7 is swung inwardly 85 toward the top of the stove, the side walls 3 being swung inwardly to overlie the end wall 7, the legs 23 having been rotated on the pivot elements 25 until the legs extend longitudinally of the folded stove, as shown in Fig. 4. It will be understood that the flue 43 may be released from the top of the stove by manipulating the frames 40 and 35. After the flue has been removed, it can be folded out and stored within the contour of the folded stove. The door 10 is swung over on top of the walls 3, the head 15 entering between the opposed parts of the flange 2.

Fig. 8 discloses a modified way of using the stove. In Fig. 8, the opening 32 is closed by a plate 45 held in place by the frames 35 and 40. The flange or foot 44 on the flue 43 is engaged beneath the lower edge of the end wall 7, the flue extending underground. An elbow 46 is connected with the outer end 110 of the flue, a stack 47 being mounted on the upwardly projecting end of the elbow. The arrangement shown in Fig. 8 permits products of combustion to escape beneath the lower edge of a tent wall 48, and renders it unnecessary to make a hole in the tent wall 115 for the passage of the flue.

Having thus described the invention, what is claimed is:

1. A stove comprising a top having a depending flange; an end wall hinged in the angle defined by the flange and the top; side walls hinged to the flange intermediate the lower and upper edges of the flange and having end lips overlying the outer face of the end wall; and a vertically swinging door hinged to the extreme lower edge of the flange and having side lips overlying the outer faces of the side walls, the end wall being foldable against the top within the 130

flange, the side walls being foldable within the flange to overlie the end wall, and the door being foldable to overlie the side walls, the lips of the door overlying the outer face 5 of the flange when the door is folded.

2. A stove having a draft opening; frames comprising opposed arms hinged adjacent their outer edges to the stove near the opening, and oppositely disposed arms 10 projecting from opposite ends of the hinged arms in opposite directions; and a member held by all of the arms in coöperating relation to the opening.

3. A stove having a draft opening; frames 15 comprising opposed first arms hinged adja-

cent their outer edges to the stove near the opening, and oppositely disposed second arms projecting from opposite ends of the first arms in opposite directions, one end of the first arm of one frame being spaced from 20 the stove, and the free end of the second arm of the other frame being releasably engaged beneath said spaced end of the first arm, thereby to hold the frames against movement; and a member held by all of the 25 frames in coöperating relation to the opening.

In testimony that I claim the foregoing as my own, I have hereto affixed my signature.

JAMES WATSON.
